The ornamental design for multi-function pocket tool, as shown and described.

DESCRIPTION

FIG. 1 is a front perspective view of the multi-function pocket tool;

FIG. 2 is a rear elevational view thereof (the front view is a mirror image of the rear view);

FIG. 3 is a right side view thereof;

FIG. 4 is a left side view thereof;

FIG. 5 is a top plan view thereof;

FIG. 6 is a front perspective view thereof showing the tools extended outside of the tool housing; and,

FIG. 7 is a front elevational view of FIG. 6.
